VOLTAGE CONTROL

**Labeeb B. Haddad, New Haven, Conn., assignor,
by mesne assignments, to Entoleter Company,
Inc., a corporation of New Jersey**

Application January 22, 1938, Serial No. 186,307

10 Claims. (Cl. 21—102)

This invention relates to an art and apparatus for treating materials by the use of electricity, particularly the control of the electricity used in such treatment.

5 One of the objects of this invention is to provide apparatus of durable construction for carrying on an electrical treatment process in an efficient and dependable manner. Another object is to provide an art and apparatus of the above 10 character for insuring the maintenance of certain predetermined conditions within a zone where materials are being treated. A further object is to provide an art and apparatus of this 15 type for maintaining a constant effective voltage, with variations in the load conditions and the source of power. Other objects will be in part obvious and in part pointed out hereinafter.

The invention accordingly consists in the features of construction, combinations of elements 20 arrangements of parts and in the several steps and relation and order of each of the same to one or more of the others, all as will be illustratively described herein, and the scope of the application of which will be indicated in the following 25 claims.

In the accompanying drawing, in which are shown several of the various possible embodiments of the invention:

30 Figure 1 is a diagrammatic representation of the electrical circuit and certain of the mechanical parts of an electrical sterilizing apparatus showing one embodiment of my control system; and,

Figure 2 is a diagrammatic representation of 35 a portion of a modified form of control system.

Referring to the right hand side of Figure 1, illustratively, an upper electrode structure 2 is positioned directly over a plurality of electrode rollers 4. Each of the electrode rollers 4 comprises a hollow shell 6 of dielectric material, such as low power-factor glass, and an elongated electrode element 8 positioned within the dielectric shell. The electrode elements 8 comprise the lower electrode structure and cooperate with the 40 upper electrode structure 2 to form a treatment zone 10 therebetween. Apparatus (not shown) is provided for rotating rollers 4, and the packages of the product being treated are placed upon the roller at the extreme right and pass from one 45 roller to another through the treatment zone 10.

The lower electrode structure is connected to a ground connection 20 through a plurality of individual air condensers 18 and the upper electrode structure 2 is connected to one lead 12 of 50 the output side of a high potential auto-trans-

former 14 the other lead of which is grounded. Auto-transformer 14 is a translator to raise the voltage of the output of alternator 22 to which it is connected by leads 24 and 26. In this manner a high potential gradient is produced within 5 the treatment zone 10 which is normally occupied by a gaseous dielectric such as air. The dielectric properties of the packages being treated are such that when they move into the treatment zone displacing air, electrical discharges occur 10 through the packages destroying all insect life which may exist therein, including the adult, egg, pupa and larva stages. In this treatment it is important that the high potential be great enough to thoroughly treat the material but at 15 the same time there should be no danger of spark discharges which might injure the packages or the product.

In some installations the amount of current flowing when packages are within the treatment 20 zone is large enough to cause an appreciable load upon the alternator 22 resulting in a reduction of its speed. Also, the source of power, shown as a commercial three-phase circuit energizing a motor 42, might vary in frequency or voltage to 25 change the alternator speed. Any change in the speed of the alternator causes a corresponding change in its output voltage and frequency, and at the same time there are changes in its synchronous reactance. The changes in speed also 30 cause changes in the field current of alternator 22 which is supplied by an exciter 46 through an adjustable rheostat 48. These changes in frequency also cause changes in the reactances of the other units in the system such as, auto-transformer 14 and the electrode structure including 35 condensers 18. When relatively high frequencies are used these various changes are appreciable, and under some conditions of operation small changes in alternator speed cause excessive 40 changes in the effective high potential.

For purposes of clarity the synchronous reactance of alternator 22 is shown separately and is designated by the numeral 40 connected in lead 26. With this type of mechanism the primary 45 current of autotransformer 14 is normally leading, having a relatively small in-phase component and an out-of-phase component leading the voltage by 90°. This is due to the fact that this apparatus is normally operated at relatively high 50 voltages and frequencies. Under normal operating conditions there is very little secondary current flow from auto-transformer 14 to the electrodes when there are no packages within the treatment zone, but when a package moves into 55

the treatment zone the current flow rapidly increases, and the corresponding primary current is leading. Synchronous reactance 40 materially affects the load-voltage or regulation characteristics of the alternator. This is especially true due to the fact that the 90° out-of-phase leading component of the load current, when flowing through synchronous reactance 40, sets up a voltage which lags this leading current by 10 90°, and thus is in phase with the alternator voltage. As a result of this, when the load current increases due to a package moving into the treatment zone, there is an increase in the output voltage of the alternator and this increase may 15 be sufficient to cause surges in the circuit and an excessive high potential gradient within the treatment zone.

In order to avoid these undesirable effects a series condenser 28 is provided in the circuit 20 which has a capacitive reactance value slightly less than the value of synchronous reactance 40 and compensates for the effect thereof. The voltage across this condenser, resulting from the 90° out-of-phase leading component of current, 25 leads this component by 90° and thus is 180° out of phase with the alternator voltage. In this manner the voltage across condenser 28 is directly opposed to the alternator voltage and the voltage caused by synchronous reactance 40. 30 As pointed out above, the value of condenser 28 is slightly less than the value of synchronous reactance 40 and, thus, the compensating voltage across condenser 28 is slightly less than the increase in voltage caused by synchronous reactance 40 with the result that there is a rise in 35 the voltage across the input side of auto-transformer 14. This rise in voltage is sufficient to compensate for the drop in voltage caused by the resistance in the circuit. In this way the value 40 of condenser 28 is such that it maintains constant voltage on the input side of auto-transformer 14 even though there are rapid changes in the load current. Condenser 28 is also effective to limit surges in the circuit and variations 45 in the voltage across the input side of auto-transformer 14 which might otherwise result from variations in the speed of alternator 22.

As indicated above, auto-transformer 14 draws a leading current and in order to maintain 50 the line current at a minimum, a resonance coil 38 is connected in parallel with the primary of the auto-transformer. Resonance coil 38 draws a lagging current and its value is such that a condition of parallel resonance exists at no load 55 and at approximately the normal operating frequency. Thus, at this resonant frequency, the out-of-phase lagging current of resonance coil 38 equals the out-of-phase leading current drawn by the auto-transformer and the current flowing in leads 24 and 26 is substantially in phase with the voltage.

The relative values of the various elements of the circuit are such that a condition of series 60 resonance occurs between condenser 28 and the total equivalent inductive reactance within the circuit. This total equivalent inductive reactance includes synchronous reactance 40 and the equivalent reactance of resonance coil 38 and auto-transformer 14 in parallel and this resonance condition occurs at a frequency below the normal operating frequency. In order to avoid excessive voltages at this resonance frequency when alternator 22 is being brought up to normal speed, a shunt circuit is provided to by-pass the current 70

of the lower frequencies around condenser 28. This shunt circuit consists of a resistor 32 connected in series with a parallel resonant circuit comprising a condenser 34 and an inductance 36.

The values of condenser 34 and inductance 36 are such that they are in parallel resonance at or near the operating frequency; thus, during normal operation, very little current flows through this shunt circuit and the action of condenser 28 is not interfered with, but at lower frequencies 10 the reactance of this shunt circuit is very small and condenser 28 is made ineffective because very little current flows through it. The current flowing through the shunt circuit is limited by resistor 32, but as this current is very small during 15 normal operation, there is no great loss of power at this resistor.

Inductance 36 is variable and may be adjusted so that resonance of the shunt circuit occurs at a frequency either above or below the normal operating frequency. Furthermore, the value of condenser 28 with respect to synchronous reactance 20 40 may be such as to cause either a rising or a falling load-voltage characteristic. Thus, by fixing the values of resonance coil 38, series condenser 28 and inductance 36, the effective input voltage to auto-transformer 14, and hence the high potential gradient within the treatment zone is reliably controlled, and will automatically remain within certain predetermined limits. The 25 apparatus may be adjusted so that the potential gradient will either remain constant or vary along a predetermined curve when there are variations in the alternator speed and load conditions. 30

An alternative circuit is shown in Figure 2 35 where condenser 58 replaces condenser 28 and is in series with a condenser 54 and an inductance 56. Condenser 54 and inductance 56 are shunted by a resistor 52. The values of condenser 54 and inductance 56 are such that they are in series 40 resonance at a frequency near the normal operating frequency. During the starting period, as alternator 22 is being brought up to speed, the circuit of condenser 54 and inductance 56 has a very high capacitive reactance and the current is 45 shunted through resistor 52, but at the normal operating frequency the reactance of condenser 54 and inductance 56 is very small and very little current flows through resistor 52. Inductance 56 50 may be adjusted in the same manner as may inductance 36 so as to obtain any predetermined condition of voltage regulation.

With apparatus of this character, the frequency and voltage of the high potential may 55 be varied over wide ranges depending upon the particular installation and the conditions of operation. It has been found that a frequency of 1020 cycles per second at a potential of 30,000 to 200,000 volts is very satisfactory under some 60 conditions.

It will thus be seen that I have provided a practical and efficient system and apparatus for accomplishing the several objects hereinabove mentioned as well as many others in a successful manner.

As many possible embodiments may be made of the mechanical features of the above invention and as the art herein described might be varied 70 in various parts, all without departing from the scope of the invention, it is to be understood that all matter hereinabove set forth, or shown in the accompanying drawing is to be interpreted as illustrative and not in a limiting sense.

I claim:

1. In electrical apparatus in which a product is treated in a treatment zone by subjecting it to the electrical discharges resulting from impressing a high potential of a predetermined value upon an electrode structure, the combination of, an electrode structure positioned to define a treatment zone, a high potential transformer having its output side connected to said electrode structure and its input side connected to an alternator by electrical conductor means, a first condenser connected in said electrical conductor means, a first inductance connected in parallel with the input side of said transformer, and a shunt circuit connected around said first condenser including a second condenser and a second inductance in parallel, the respective values of the inductance and the capacity of the various elements being such that at or near the normal operating frequency of said apparatus said second condenser and said second inductance are at parallel resonance and the potential gradient within the treatment zone is reliably regulated.
2. In electrical apparatus in which a product is treated in a treatment zone by means of electrical discharges resulting from impressing a high potential of predetermined value upon an electrode structure, the combination of, an electrode structure positioned to define a treatment zone, and an electrical circuit connected to said electrode structure including, an alternator, a main condenser unit connected in series with the output of said alternator, and a condenser-inductance resonance unit electrically connected with said main condenser unit, the respective values of the inductance and the capacitance of the elements being such that said resonance unit is in resonance at or near the normal operating frequency of said apparatus and the potential gradient within the treatment zone is reliably regulated.
3. In electrical apparatus in which a product is treated in a treatment zone by means of electrical discharges resulting from impressing a high potential of predetermined value upon an electrode structure, the combination of, an electrode structure positioned to define a treatment zone, and an electrical circuit connected to said electrode structure including, an alternator, a main condenser unit connected in series with the output of said alternator, and a shunt circuit connected around said main condenser unit including a second condenser and an inductance in parallel, the respective values of the inductance and the capacitance of the elements being such that at or near the normal operating frequency of said apparatus said second condenser and said inductance are in parallel resonance and the potential gradient within the treatment zone is reliably regulated.
4. In electrical apparatus in which a product is treated in a treatment zone by means of electrical discharges resulting from impressing a high potential of predetermined value upon an electrode structure, the combination of, an electrical structure positioned to define a treatment zone, and an electrical circuit connected to said electrode structure including, an alternator, a main condenser unit connected in series with the output of said alternator, and a resonance unit in series with said main condenser unit, said resonance unit comprising a second condenser and an inductance, the respective values of the inductance and the capacitance of the elements being such that they are in series resonance at or near the normal operating frequency and the potential gradient within the treatment zone is reliably regulated.
5. In electrical apparatus in which a product is treated in a treatment zone by means of electrical discharges resulting from impressing a high potential of predetermined value upon an electrode structure, the combination of, an electrode structure positioned to define a treatment zone, and an electrical circuit connected to said electrode structure including, an alternator, a main condenser unit connected in series with the output of said alternator, and a control unit including a resistance unit and a condenser-inductance resonance unit electrically connected with said main condenser unit, the respective values of the inductance and the capacitance of the elements being such that said resonance unit is in resonance at or near the normal operating frequency of said apparatus and said resistance unit being of a value to prevent an excess flow of current—whereby said main condenser unit is rendered substantially ineffective except within the normal frequency range and the potential gradient within the treatment zone is reliably regulated.
6. In electrical apparatus in which a product is treated in a treatment zone by means of electrical discharges resulting from impressing a high potential of predetermined value upon an electrode structure, the combination of, an electrode structure positioned to define a treatment zone, and an electrical circuit connected to said electrode structure including, an alternator, an inductance unit electrically connected in parallel with said electrode structure, a main condenser unit connected in series with the output of said alternator, and a condenser-inductance resonance unit electrically connected to regulate the current flowing through said main condenser unit, the respective values of the inductance and the capacitance of the elements being such that said resonance unit is in resonance at or near the normal operating frequency of said apparatus and the potential gradient within the treatment zone is reliably regulated.
7. In apparatus of the class described, the combination of: an alternator for producing an alternating current of substantially constant voltage; treating apparatus having a pair of electrode structures between which a high potential gradient is produced; and circuit means connecting the output of said alternator across said electrode structures including, a main condenser unit connected to carry the normal alternator output current and compensate for variations in output voltage due to the inductive impedance of said alternator, and a frequency-responsive current controlling unit to render said main condenser substantially ineffective except within the normal range of operating frequencies, said current controlling unit including a resonance circuit connected with a resistance unit to cause the major portion of the current flowing in the main circuit at frequencies other than the normal range of operating frequencies to flow through said resistance unit and to prevent the flow of a substantial current through said resistance unit during normal operation.
8. In apparatus of the class described, the combination of: an alternator for producing an alternating current of substantially constant voltage; treating apparatus having a pair of electrode structures between which a high potential gradient is produced; and circuit means connecting the output of said alternator across

said electrode structures including, a main condenser unit connected to carry the normal alternator output current and compensate for variations in output voltage due to the inductive impedance of said alternator, and a frequency-responsive unit including a resistance unit and a resonance unit connected to prevent the flow of a substantial amount of current through said main condenser at frequencies other than the 10 normal operating frequencies.

9. In apparatus of the class described, the combination of: an alternator for producing an alternating current of substantially constant voltage; treating apparatus having a pair of electrode structures between which a high potential gradient is produced; and circuit means connecting the output of said alternator across said electrode structures including, a main condenser unit connected to carry the normal alternator 15 output current and compensate for variations in output voltage due to the inductive impedance of said alternator, and a frequency-responsive shunt circuit connected to by-pass said main con-

denser unit, said shunt circuit comprising a resistance unit in series with a parallel resonance unit which is resonant at substantially the normal operating frequency.

10. In apparatus of the class described, the combination of: an alternator for producing an alternating current of substantially constant voltage; treating apparatus having a pair of electrode structures between which a high potential gradient is produced; and circuit means 10 connecting the output of said alternator across said electrode structures including, a main condenser unit connected to carry the normal alternator output current and compensate for variations in output voltage due to the inductive impedance of said alternator, a resistance unit in series with said main condenser unit, and a series resonance circuit connected across said resistance unit and being resonant at substantially the normal operating frequency to thereby by-pass said resistance unit during normal 15 operation.
